ELECTRON DISCHARGE DEVICE

Harold A. Wheeler, Great Neck, N. Y., assignor to
Hazelton Corporation, a corporation of Delaware

Application March 23, 1933, Serial No. 662,203
Renewed July 11, 1934

16 Claims. (CL 250—27.5)

This invention relates to electron discharge devices, and more particularly to devices of this character having a grid element, with a non-uniform pitch, or grid mesh.

5 This is a continuation in part of my copending application Serial No. 654,327, filed January 30, 1933.

It is an object of this invention to provide an electron discharge device of which the gain may 10 be readily controlled by the application of a biasing voltage to a grid; and a particular object is to provide a modulator tube of which the conversion gain can thus be readily controlled.

In a preferred embodiment for carrying out the above objects, there is provided a vacuum tube having six electrodes, namely, an electron-emitting cathode and an anode in the form of a plate, in the space path between which are located four other electrodes. These four latter 20 electrodes are in the form of screens or grids and are located at successively increasing distances from the electron-emitting element, the first of these screens or grids being designated as that closest to the said emitting element.

25 A feature which makes a device according to this invention readily subject to a control biasing voltage, and hence well-suited as a controllable modulator is the construction of the control grid. This control grid is formed of a mesh having a 30 variable spacing or pitch, so that the resulting characteristic imparted to the device is in the form of a gradual curve having no sharp bend, or cutoff, in the operating range. It is well-known that a type of characteristic which is well-suited 35 to permit effective gain control over a range of controlling biasing voltages is that in which the curve of mutual conductance versus biasing voltage is a straight line when plotted on log-linear coordinates. This is known as an exponential 40 curve. Control grids for providing this relation are known as exponential grids.

45 I have found that the curve of mutual conductance versus grid bias can be predetermined by the manner in which the grid spacing, or pitch, is made to vary throughout its length. I have ascertained by experiment that if the grid mesh is 50 varied in such a way that the graph of serial numbers of successive grid meshes plotted against the pitch on log-log coordinates is a straight line, the 55 serial number 1 being the grid mesh of greatest spacing and the last serial number being the grid mesh of finest spacing, the curve of mutual conductance versus grid bias will be of the desired exponential type. The absolute values of mutual 60 conductance for a given grid bias and its variation with grid voltage, that is, the slope of the log-linear curve or line, may be adjusted as desired by suitably sloping and/or positioning the log-log curve of serial numbers versus pitch with respect to its origin of coordinates, or by leaving

the log-log curve in its initial position and suitably varying the log-log scales with respect thereto.

As a practical matter, the grid can be designed to meet the above requirements by proportioning the lateral pitch of the spaces or meshes between adjacent grid structural elements to be substantially in the inverse ratio of a predetermined fractional power of the number which is assigned to each space by serially numbering the spaces in 10 the order of decreasing pitch. 5

In the drawings:

Figure 1 illustrates an electron discharge device in accordance with this invention, a portion of the glass-enclosing vessel being cut away to show 15 more clearly the position of the electrodes within;

Fig. 2 is a vertical sectional view of the device showing in detail its construction and the positions of the elements; 20

Fig. 3 is a broken diagram showing in perspective the construction of the elements and also indicating the manner of connecting operating voltages which place the device in an operative condition; 25

Fig. 4 is a plan view, in section, of the electrode construction;

Fig. 5 is an enlarged illustration, partially in section, of the cathode electrode and the means for heating the same; 30

Fig. 6 is a graph showing a relation between mutual conductance and grid bias which provides a desirable type of characteristic;

Fig. 7 is a graph illustrating a method of designing a grid to provide a desired relationship 35 similar to that of Fig. 6, in accordance with this invention; and

Fig. 8 is a graph similar to that of Fig. 7 illustrating the manner of obtaining a closer approximation to the desired characteristic. 40

Figure 1 illustrates an electron discharge device similar to that illustrated in my above-mentioned application Serial No. 654,327, but differing therefrom in having an improved form of control grid. The device comprises an evacuated 45 glass bulb 10, the stem end of which is fitted into a bakelite base 11 in which are embedded seven projecting terminal lugs, numbered 12 to 18, respectively, adapted to fit into a suitable socket. An eighth terminal 19 is situated at the 50 top of the bulb in the form of a metallic cap cemented to the glass. The electrodes of the device are supported by a number of vertical supporting wires embedded in a glass stem 20 formed on a reentrant portion 21 at the stem end of the 55 bulb (see Fig. 2). For the purpose of maintaining the supporting wires rigidly in their upright position, there are provided two flat guides 22 and 23 of an insulating material, such as mica, through which the supporting wires project. The 60

upper guide 22 is constructed to snugly fit within the dome-like end of the glass bulb.

The following electrode construction is employed: A cathode 1 in the form of a sleeve of very small diameter is centrally located within the bulb. This sleeve is preferably constructed of nickel coated with strontium and barium oxides for the purpose of causing it to copiously emit electrons when heated. For the purpose of heating the cathode sleeve, there is located within the sleeve a heater filament 38 of fine wire, preferably of tungsten, coated with ceramic insulation and threaded back and forth within the sleeve in the form of a W as shown in Fig. 5. The ends of the heater filament are connected to the large-diameter terminal lugs 12 and 13 at the base.

Surrounding the cathode at a small distance therefrom is an inner grid electrode 2 in the shape of an elliptical cylinder formed by a helix of fine wire and supported on two of the vertical supporting wires 24 and 25. This grid electrode is preferably wound with a relatively small pitch (distance between adjacent turns) which is uniform throughout. The construction of this particular grid, however, is not critical. Fig. 4, which is a plan view of the electrode construction, shows the elliptical form of grid-electrode 2 and also of the remaining electrodes about to be described. The major axis of each ellipse is only slightly greater than the minor axis.

A second grid-like electrode 3, here called an inner screen, is constructed in the form of an elliptical cylinder by winding a helix of wire which surrounds the first grid 2, the second grid-like electrode being supported on the two supporting wires 26 and 27. This second helix is of fine mesh, that is, has a small pitch, which is preferably uniform throughout. As thus far described, the device is the same as that of my application Serial No. 654,327.

The improvement over the tube of my said original application, provided by this invention, resides in the construction of the third grid electrode 4. This third grid surrounds the electrode 3, and is likewise formed by a helix of wire in the shape of an elliptical cylinder supported on supporting wires 28 and 29; but the pitch or mesh of this electrode is not uniform throughout its extent. As this is the grid upon which it is intended to impress a biasing voltage for controlling the conversion gain of the tube, it is desired that this grid be proportioned to provide a gradual cutoff, of a type in general characterizing the so-called variable-mu tubes, so that wide ranges of control bias will not deleteriously alter the tube performance.

It is the purpose of the grid construction about to be described to provide the most advantageous tube characteristic for this purpose. It is known that such a highly satisfactory characteristic exists when the curve of grid bias versus mutual conductance is a sloping straight line when plotted on log-linear coordinates. This desired type of curve is illustrated in Fig. 6 wherein the abscissas represent negative bias plotted on a linear scale and the ordinates represent mutual conductance plotted on a logarithmic scale. The sloping portion of the curve marked "exponential" shows the ideal characteristic, which should extend throughout the range of grid bias employed. The vertical portion of the curve marked "sharp cutoff" represents the bend usually experienced to a greater or less degree in vacuum tubes; and

in this case is located beyond the range of bias voltage.

Although it has been known that the grid bias versus mutual conductance characteristic (and hence the cut-off characteristic) is dependent more or less upon the form or pitch of the control grid, it has not been known how to accurately predetermine this characteristic. Consequently, heretofore the design of a grid was worked out by the cut-and-try method which even then did not produce a very close approximation to the desired result. I have ascertained that the desired straight line log-linear relationship between grid bias and mutual conductance is obtained when the relationship between the serial number of the grid turns and the pitch of the turns is a similar linear line when plotted on log-log coordinates. In arriving at this relationship, the mentioned serial number of the grid turns is expressed in the order of decreasing pitch, regardless of the location of the turns in the grid.

The construction is represented graphically in Figure 7 wherein the logarithmic coordinate m represents serial numbers of turns and the logarithmic coordinate p represents pitch per turn in mils of each turn (numbered m). The dotted line 50 represents the desired log-log relationship (this being a typical straight line log-log characteristic curve). Inasmuch as no less than a single turn of grid winding is considered, the actual graph is represented by the irregular line 51. The numbers $1t$, $2t$, etc., at the left of the graph indicate the number of turns in each group of turns having the same pitch; and the designations 69 mils, 54 mils, 41 mils, etc., represent the pitch of each turn of the corresponding group. Thus the portion of the graph designated $1t$, 69 mils, indicates that one of the grid turns has a 69 mil pitch (the largest pitch of the grid); and the portion marked $16t$, 19 mils, indicates that sixteen of the grid turns have a 19 mil pitch. It follows, then, that the pitch used in this particular construction varies from 69 mils of which there is one turn down to 19 mils of which there are 16 turns. It is observed that each group includes one or more turns to which are assigned the serial numbers indicated by the ordinates of the graph. Although the line 51 is drawn as a discontinuous curve, there are actually experienced no sharp bends in the tube characteristic; for, as is well known, vacuum tubes are not characterized by a pronounced bend for each grid turn or group of turns.

As stated above, it has been found that, if a grid is so constructed that a plot of the grid-turn serial numbers versus pitch on log-log scales is a straight line, the desired type of control grid characteristic may be obtained. That is to say, by proportioning the grid meshes in accordance with a straight line as plotted on log-log scales, the grid will provide a curve of mutual conductance versus biasing voltage which is exponential. In other words, the latter curve will be a straight line when plotted on log-linear scales; the same type as the curve of Fig. 6. Having thus provided this type of characteristic, it is obvious that the identical characteristic of Fig. 6 may be obtained by suitably adjusting the position and/or slope of the line 50, Fig. 7, or by leaving the line 50 in its original position and suitably varying the scales with respect thereto.

It is recommended, although it is not essential, that the lower serial numbered turns be located at the middle of the grid, and the higher serial numbered turns be arranged alternately in sec-

tions toward the two ends of the grid, so that the smallest pitch is at the ends. A preferred arrangement is indicated in Fig. 7 by the designations "above" and "below" adjacent the several groups of turns, the designation "above" signifying that the group of turns is situated above a reference point which is practically the central portion of the grid, and the designation "below" signifying that the group of turns is located below the reference point. The arrangement of the several groups of turns of the grid is more clearly shown by the following table, wherein the groups are listed in the order of their position from the upper to the lower end of the grid, the terms "upper" and "lower" corresponding to the terms "above" and "below" used heretofore.

Serial numbers <i>m</i>	No. turns in group	Pitch of turns in group <i>p</i> (mils)	Axial length of group (mils)
17-32	16	19	304
5-8	4	32	128
2	1	64	64
1	1	60	60
3-4	2	41	82
9-16	8	25	200
			837 (length of grid)
	32 (total turns)		

The grid 4 of Figs. 2 and 3 has been proportioned in accordance with the above table.

Figure 8 shows how a closer approximation to the ideal characteristic can be obtained. This figure is a chart having the same coordinates as Figure 7, and similar designations, the principal difference being that the dotted straight line 52, taken as ideal, is more closely approximated by means of a finer grading of the pitch throughout the extent of the grid, as shown by the discontinuous line 53. The following table indicates a recommended arrangement of a grid constructed in accordance with Fig. 8.

Serial numbers <i>m</i>	No. turns in group	Pitch of turns in group <i>p</i> (mils)	Axial length of group (mils)
25-32	8	18	144
13-16	4	23	92
7-8	2	30	60
4	1	40	40
2	1	51	51
1	1	66	66
3	1	44	44
5-6	2	34	68
9-12	4	26	104
17-24	8	20	160
	32 (total turns)		829 (length of grid)

If desired, the grid, instead of being formed in groups of turns of equal pitch as indicated in the tables associated with Figs. 7 and 8, may be formed by placing the serial number 1 turn at the middle of the grid and proceeding alternately in serial numbers toward both ends. The location of the serial numbers from one end to the other, in this arrangement, is indicated as follows:

31, 29, 27 . . . 5, 3, 1, 2, 4, 6 . . . 28, 30, 32.

Alternatively, the grid may be designed by using two sets of serial numbers, each set commencing at the middle with serial number 1 and extending toward either end. The order of the turns will then be:

. . . 4, 3, 2, 1, 1, 2, 3, 4, . . .

or

. . . 4, 3, 2, 1, 2, 3, 4, . . .

In the above-described type of grid construction the following relationships obtain:

$$p_m = \frac{p_1}{m^c} \quad (1)$$

$$p_n = \frac{p_1}{n^c} \quad (2)$$

$$b = \frac{np_n}{(1-c)} \quad (3)$$

$$n = \frac{p_1}{p_n} \quad (4)$$

$$n = \frac{b(1-c)}{p_n} \quad (5)$$

where:

m=serial number of each turn, in order of decreasing pitch.

n=total number of turns.

p=pitch per turn (mils).

p_n=pitch of the turn having the smallest pitch (the *n*th turn).

p_m=pitch of the *m*th turn.

p₁=pitch of single turn having greatest pitch (m=1).

p=average pitch.

b=np_n=axial length of grid.

c=exponent indicating inverse slope of dotted lines in Figures 7 and 8.

The exponent *c* is the actual inverse slope of the dotted lines 50 or 52; and must be substantially less than unity, otherwise the above equations fail. This exponent should usually be held within the ranges of .3 to .4. The values of *c*, *n* and *b* are given in Figs. 7 and 8.

An inspection of Equation (1), above, shows that the grid is properly constructed when the pitch of the spaces between adjacent grid turns is proportioned substantially in the inverse ratio of the *c*th power of *m*, that is, in the inverse ratio of a predetermined fractional power of the number which is assigned to each grid mesh, or space, by serially numbering the spaces in the order of decreasing pitch.

In the case of the grid structures represented by Figs. 7 and 8, Equation (1) becomes

$$p_m = \frac{p_1}{m^{1/3}} \quad (6)$$

The exponent applied to *m* is therefore substantially $\frac{1}{3}$, which is the cube root.

Surrounding the third grid, and supported on supporting wires 30 and 31, is a fourth grid-like electrode 5, here called an outer screen, also constructed of a helix in the form of an elliptical cylinder. This fourth grid-like electrode preferably has a relatively fine mesh which is uniform throughout.

Finally, a plate 6, in the form of a cylinder, is provided which surrounds the entire grid-electrode structure, the plate being supported on supporting wires 32 and 33. The plate is preferably constructed of carbonized nickel and its axial length is not as great as that of the other electrodes.

Constructional data for the electrodes other than the third grid electrode, or outer grid 3, which have been found very satisfactory, are as follows:

Inner grid 2—major axis, 0.121 inch; minor axis .096 inch; wound with 25 turns of .004 inch diameter wire with a .033 inch uniform pitch.

Inner screen 3—major axis, 0.236 inch; minor 75

axis, 0.167 inch; wound with 33 turns of .005 inch wire with a .025 inch uniform pitch.

Outer screen 5—major axis, 0.490 inch; minor axis, 0.460 inch; wound with 33 turns of .005 inch diameter wire, with a .025 inch uniform pitch.

It is usually desirable to carbonize the inner wall of the glass bulb or vessel, as indicated in Figure 1 by the dotted portion of the glass; this, however, is a refinement which may be omitted.

10 The connection of operating voltages which place the device in a very advantageous operative condition, particularly for use as a modulator, is illustrated in Figure 3. There is connected across terminal lugs 12 and 13 a battery 34 (or other source of filament heating current) which serves to heat the W-type filament 38 within the cathode sleeve, the said cathode itself being nominally grounded by the ground connection at terminal 14. Batteries 35, 36, and 37, or other sources of 15 direct voltage are connected between ground and the terminals 16, 17, and 18, respectively, for applying positive voltages to the inner screen 3, the outer screen 5 and the plate 6, respectively. A negative bias battery 39 is connected between 20 ground and the cap 19 for placing a negative bias upon the non-uniform mesh, outer grid 4.

With the above-described system of operating voltages, the action of the device is as follows: 0 the heated cathode 1 emits electrons which are attracted to the inner screen 3 by virtue of the positive voltage applied to the latter. The electrons upon reaching the screen 3 are traveling at a high speed so that most of them pass on through the screen and approach the outer grid 4, the 5 negative potential of which retards the electrons and causes most of them to be attracted back to the positive screen. This retarding action causes a cloud of slowly-moving electrons to accumulate between the electrodes 3 and 4. Hence, the position 0 of this cloud may be termed a "virtual cathode" because of the fact that the electrons can be easily drawn away from the cloud in the same manner that they were originally drawn away from the vicinity of the actual cathode 1. 5 Since the screen 5 and plate 6 are at a positive voltage, this is exactly what happens, a stream of electrons being drawn from the "virtual cathode," through the meshes of the grid-like electrodes 4 and 5 to the plate. Electrodes 4, 5, 0 and 6 function similarly to the respective control grid, screen and plate of screen-grid tetrode tubes. The outer screen 5 will usually have applied to it a source of positive voltage somewhat less than that of the plate in the preferred manner of 5 screen-grid tubes.

The electron-discharge device in accordance with this invention has been found to be very useful where it is desired to exert a control upon the action of a vacuum tube without actually introducing into a circuit or space path of that tube external elements which would not very successfully cooperate. For example, the repeating portion of the tube may be considered to have input terminals which are the outer grid 4 and the 5 "virtual cathode," and to have output terminals which are the plate 6 and the virtual cathode. Since the potential of the "virtual cathode" is the same as that of the actual cathode, it is found that input signals impressed between terminals 14 and 18 will be repeated at the output between terminals 18 and 14.

The desired modification of the input signals can then be effected by applying the modifying voltage to the inner grid 2, that is, between terminals 14 and 15. This modifying voltage may

often be a simple alternating voltage, which then causes the entire device to operate as a modulator. The effect of the voltage on the grid 2 is to modify the electron stream which flows to the virtual cathode and hence indirectly to modify 5 the space current between the virtual cathode and the plate.

Since the electrodes 4, 5, and 6 exert very little effect on the space current to electrodes 2 and 3, the inner and outer control grids 2 and 4 may 10 be operated quite independently of each other. For example, it is quite possible and convenient to vary the negative bias applied to the outer control electrode 4; and this may be easily accomplished without affecting the action of any 15 modifying voltage applied to inner grid 2. This variation of the negative bias of the outer grid 4 is a very convenient expedient inasmuch as it permits a very simple control of the responsiveness of the device.

20 The non-uniform spacing of the meshes of control grid 4, in accordance with the above-described design, permits a wide range of bias voltage to be applied with the least amount of signal distortion, and practically eliminates 25 interference with the normal action of electrodes 2 and 3.

The outer screen 5 may be omitted, but its presence greatly improves the results, particularly in obtaining the greatest responsiveness. 30 This screen, in general, performs the function of a similar screen in the well-known screen grid tetrode, and is therefore usually given a positive voltage somewhat less than that of the plate.

35 Although the form of grid construction in accordance with this invention has been applied to the preferred embodiment, which is a hexode oscillator-modulator form tube, it should be understood that this form of grid construction is 40 not limited to hexodes or oscillator-modulator tubes, but has application in any tube to which it is desired to impart a gradual cutoff characteristic.

45 Where the control grid operates upon a virtual cathode, as in the preferred oscillator-modulator embodiment, the exponent c should be held fairly small, of the order of .3 to .4. Somewhat larger values of c , however, may be employed when the control grid operates upon a real cathode, and when a very broad cutoff is desired.

50 The graphical method of predetermining the mechanical dimensions of a grid, as herein employed in the design of exponential grids, is also applicable to the design of grids which are intended to provide predetermined relations other than exponential.

55 I claim:

1. A vacuum tube grid structure composed of a helix of an electrical conducting material of 60 which the adjacent grid turns are spaced in relation to each other so that the ratio of the space between any turn to the space between the most widely spaced turns is inversely proportional to a fractional power of the serial number which is assigned to the spaces by serially numbering these spaces in the order of decreasing space width.

65 2. The structure of a grid electrode for a vacuum tube, comprising a plurality of laterally spaced elements, the lateral pitch of the spaces between adjacent elements being proportioned substantially in the inverse ratio of a fractional power of the number which is assigned to each 70 75

inter-element space by serially numbering the spaces in the order of decreasing pitch.

3. A non-uniform-pitch helical grid electrode for a vacuum tube, having the pitch of its turns proportioned substantially in the inverse ratio of a fractional power of the number which is assigned to each turn by serially numbering the turns in the order of decreasing pitch.

4. A non-uniform-pitch helical grid electrode for a vacuum tube, having the pitch of its turns proportioned substantially in the inverse ratio of the cube root of the number which is assigned to each turn by serially numbering the turns in the order of decreasing pitch.

15 5. A non-uniform-pitch helical grid electrode for a vacuum tube, having the pitch of its turns proportioned substantially in the inverse ratio of a predetermined fractional power of the number which is assigned to each turn by serially numbering the turns, starting with unity in the middle of the grid and proceeding alternately toward both ends.

25 6. A non-uniform-pitch helical grid electrode for a vacuum tube, having the pitch of its turns proportioned substantially in the inverse ratio of a predetermined fractional power of the number which is assigned to each turn by serially numbering the turns outward from the middle of the grid, using odd numbers from unity increasing toward one end, and using even numbers from two increasing toward the other end.

35 7. A non-uniform-pitch helical grid electrode for a vacuum tube, having the pitch of its turns proportioned substantially in the inverse ratio of a predetermined fractional power of the number which is assigned to each turn by serially numbering the turns from the middle toward each end of the grid.

40 8. A non-uniform-pitch helical grid electrode for a vacuum tube, having the pitch of its turns proportioned substantially in the inverse ratio of a predetermined fractional power of the number which is assigned to each turn by serially numbering the turns in the order of decreasing pitch, the turns of smallest pitch being located nearest the ends of said grid electrode.

45 9. A non-uniform-pitch helical grid electrode for a vacuum tube, having the pitch of its turns proportioned substantially in the inverse ratio of a predetermined fractional power of the number which is assigned to each turn by serially numbering the turns in the order of decreasing pitch, the turns of greatest pitch being located near the middle of said grid electrode.

55 10. An electron discharge device comprising an evacuated bulb having a cathode, an anode, and at least three grid-like electrodes located in the space path between said cathode and said anode, each of said electrodes being located at a different distance from the cathode and the third of said electrodes in point of distance from said cathode having a non-uniform pitch of meshes, said pitch being proportioned substantially in the inverse ratio of a fractional power of the number which is assigned to each mesh by serially numbering the meshes in the order of decreasing pitch.

60 11. An electron discharge device comprising an evacuated bulb having located therewithin a centrally located cathode, at least three grid-like electrodes of a cylindrical form surrounding said cathode, said three electrodes being of successively increasing diameters, each successive electrode surrounding those of smaller diameter, and

65 electrode of intermediate diameter having meshes of non-uniform pitch, said pitch being proportioned substantially in the inverse ratio of a fractional power of the number which is assigned to each mesh by serially numbering the meshes in the order of decreasing pitch.

70 12. An electron discharge device comprising a closed bulb containing a centrally located cathode, a cylindrical plate laterally surrounding said cathode, and four cylindrical electrodes of a mesh construction also laterally surrounding said cathode but laterally surrounded by said plate, each succeeding electrode surrounding the one preceding, and each of said mesh-formed electrodes being constructed in the form of a helix, the 15 helix forming the third of said mesh-formed electrodes, in point of distance from said cathode, having a pitch of winding which is proportioned substantially in the inverse ratio of a fractional power of the number which is assigned to each 20 mesh by serially numbering the meshes in the order of decreasing pitch.

75 13. An electron discharge device comprising a closed vessel containing a cathode, a cylindrical plate laterally surrounding said cathode and four 25 cylindrical grid-like electrodes laterally surrounding said cathode, but laterally surrounded by said plate, each succeeding electrode surrounding the one preceding, and each of said grid-like electrodes being constructed of a helix 30 of wire, the helix forming the first, second and fourth of said grid-like electrodes, in point of distance from said cathode, having a uniform spacing between adjacent turns of wire, and the helix forming the remaining of said electrodes 35 having a spacing between its adjacent turns proportioned substantially in the inverse ratio of a fractional power of the number which is assigned to each space by serially numbering the spaces in the order of decreasing pitch.

80 14. An electron discharge device comprising a closed vessel having located therein a centrally located cathode, four cylindrical grid-constructed electrodes surrounding said cathode at successively increasing distances therefrom and an 45 anode surrounding said electrodes, the third of said grid-constructed electrodes, in point of distance from said cathode, having spaces between successive grid elements which are proportioned substantially in the inverse ratio of a fractional 50 power of the number which is assigned to each space by serially numbering the spaces in the order of decreasing pitch.

85 15. An electron discharge device comprising in a closed bulb a plurality of co-axial concentric 55 cylindrical electrodes of graduated diameters, the fourth from the inside being a helical grid of non-uniform mesh along its axial dimension, the spaces of said mesh being proportioned substantially in the inverse ratio of a fractional power 60 of the number which is assigned to each mesh by serially numbering the meshes in the order of decreasing pitch, the third and fifth electrodes from the inside being helical screens of uniform fine mesh, and the outermost of said electrodes 65 being a cylindrical plate.

90 16. The method of constructing a vacuum tube grid which comprises winding a helix of wire and spacing the adjacent grid turns so that the spaces vary in the inverse ratio of a fractional 70 power of the number which is assigned to each space by serially numbering the spaces in the order of decreasing pitch.

CERTIFICATE OF CORRECTION.

Patent No. 2,016,760.

October 8, 1935.

HAROLD A. WHEELER.

It is hereby certified that error appears in the printed specification of the above numbered patent requiring correction as follows: Page 1, first column, line 48, strike out the word "the"; page 2, second column, lines 27-28, strike out the words "the desired log-log relationship (this being"; and line 29, after "curved" strike out the parenthesis; and page 4, first column, line 37, after "screen" insert 3; and that the said Letters Patent should be read with these corrections therein that the same may conform to the record of the case in the Patent Office.

Signed and sealed this 19th day of November, A. D. 1935.

Leslie Frazer

(Seal)

Acting Commissioner of Patents.
